UNITED STATES PATENT OFFICE.

SAMUEL H. WHITE, OF ANDING, MISSISSIPPI.

WIRE-STRETCHER.

1,245,079.

Specification of Letters Patent. Patented Oct. 30, 1917.

Application filed April 10, 1917. Serial No. 161,026.

To all whom it may concern:

Be it known that I, SAMUEL H. WHITE, a citizen of the United States, residing at Anding, in the county of Yazoo and State of Mississippi, have invented new and useful Improvements in Wire-Stretchers, of which the following is a specification.

This invention relates to wire stretchers and it consists in the novel features herein-
10 after described and claimed.

An object of the invention is to provide a stretcher of the character stated especially adapted to be used for drawing woven wire fabric used in fence structures whereby the
15 same may be stapled or otherwise secured to upright posts planted in the ground.

With this object in view the stretcher comprises a handle staff having prongs attached to its edges with a bracket pivoted between
20 the prongs and a hook pivotally mounted upon the said bracket.

In the accompanying drawing,—

Figure 1 is a plan view of the stretcher.

Fig. 2 is a longitudinal sectional view of
25 the same.

The stretcher comprises a handle staff 1 which is of wood or other suitable material. Metallic prongs 2 are secured to the opposite edges of the handle staff 1 and the said
30 prongs have pointed ends which project beyond the end of the handle staff. A bracket 3 is pivotally connected with the prongs 2 at a point beyond the end of the handle staff and the said bracket lies between the said
35 prongs. A hook 4 is pivotally connected with the intermediate portion of the said bracket and the said hook is bent at a point between its ends in order that it may lie flat

against the side of the handle staff when the device is not in use or when it is packed for
40 storage or transportation.

In operation, the points of the prongs 2 are placed against the sides of a post and the line wire of a fence fabric is caught in the hook 4. The handle staff 1 is then used as a
45 lever whereby the line wire is drawn trans- versely across the post and when the said line wire is sufficiently stretched, it is secured by driving a staple into the post and over the said line wire in the usual manner. Thus
50 the fence fabric is secured to the post after it has been properly stretched. When it is desired to remove the fence fabric from the post, the pointed ends of the prongs may be inserted in the staples and by using the
55 handle staff 1 as a lever, the said staples may be pried or removed from the post thus releasing the line wires and the said fabric may be quickly detached from the said post.

Having described the invention what is
60 claimed is:—

A wire stretcher comprising a handle staff, prongs attached to the opposite edges of the staff and having pointed ends which project beyond the end of the staff, a bracket
65 pivotally mounted upon the prongs at a point beyond the end of the staff, and a hook
pivotally mounted upon the intermediate portion of the bracket, said hook being bent
70 at a point between its ends whereby the free end portion of the hook may lie flat against the side of the handle staff when the device is not in use.

In testimony whereof I affix my signature.

SAMUEL H. WHITE.
